UNITED STATES PATENT OFFICE.

OLIVER S. JENNINGS, OF WILKINSBURG, PENNSYLVANIA, ASSIGNOR TO WESTINGHOUSE ELECTRIC & MANUFACTURING COMPANY, A CORPORATION OF PENNSYLVANIA.

METERING PANEL BOARDS.

Application filed March 10, 1922. Serial No. 542,741.

My invention relates to metering panel mechanism and particularly to metering panels of the inclosed type.

One object of my invention is to provide a metering panel mechanism wherein the main feed terminals and branch-line controlling mechanism are disposed in a main housing and the metering bars are disposed in a separate housing which may be located 10 at a remote point.

Another object of my invention is to provide a metering panel wherein the panels for the branch-line control mechanism are so disposed as to provide a wiring gutter between them in which the conductors for selectively connecting the metering bars to the various branch circuits may be disposed.

Another object of my invention is to provide a metering panel, having the above 20 characteristics, wherein the neutral bus bar of a three-wire circuit is supported above the wiring gutter by bridging connectors and supported clear of the insulated conductors disposed in the wiring gutter.

25 These and other objects, that will be made apparent throughout the further description of my invention, are attained by means of the apparatus hereinafter described and illustrated in the accompanying drawings, 30 wherein:

Figure 1 is a front view of the metering panel mechanism showing the main and auxiliary housings with their main covers removed;

35 Fig. 2 is a transverse section through the main housing taken on the line II—II of Fig. 1, and

Fig. 3 is a transverse section through the auxiliary housing taken on the line III—III 40 of Fig. 1.

In my co-pending application Serial No. 540,247, (Case 9087), filed March 1, 1922, I have shown a metering-panel mechanism wherein the metering bars are disposed in 45 the housing containing the main feed terminals and the branch-circuit-controlling mechanism. In certain installations, it is expedient to locate the metering bars at a point remote from the switch panel, in which case 50 provision must be made for the conductors for selectively connecting the branch circuits to the desired meters.

Referring to the drawings, it will be seen that I have provided a wiring gutter be-

tween the rows of panels containing the 55 branch circuit switches and fuses.

The panel mechanism includes a main housing 4 and an auxiliary metering-bar housing 5 that may be located at any desired point remote from the main housing or in a different room. The main housing 4 comprises a rectangular housing having a bottom plate 3 and side walls 6 that are provided with flanges 7 to which a cover 8 is secured. The housing is divided into an inner panel compartment 9 and a wiring gutter 10 which completely surrounds the compartment 9 by a rectangular partition 11.

The main feed terminals 12, 13 and 14 are disposed in the panel compartment 9 and are 70 adapted to be attached to the main feed conductors (not shown). The terminals 12 and 13 are provided with a plurality of branch conductors 30 and 40, respectively, each of which is connected to the current coil 16 of 75 separate meters 17. The conductors 30 and 40 extend along the wiring gutters 10 at opposite sides of the housing and project through outlet bushings 18 provided in the sides 6 of the housing. A separate meter is 80 provided for each branch conductor 14 and 15 and the feed current passes therethrough to the current coils of the meter and thence, by means of conductors 19, to separate meter bars 20 that are disposed longitudinally of 85 the housing 5.

The switch and fuse panels 21, one for each branch circuit, are mounted side by side in rows on opposite sides of the housing and are so disposed as to provide a space constituting a wiring gutter 22 between them. Each panel is provided with a switch 23 which, as shown, is of the tumbler type and a pair of fuse receptacles 24 that are adapted to receive fuses 25 of the screw-plug type, as 90 indicated in Fig. 2. However, receptacles containing cartridge fuses may be used. The switches are of the two-pole type and are provided with auxiliary feed terminals 26 and 27 and load terminals 28 and 29 to 100 which the load conductors 31 and 32 are respectively connected. The conductors project through the partition walls 11 into the adjacent wiring gutter 10 and extend exteriorly of the housing through the bushings 18.

The feed terminal 14 is connected to a feed bus bar 33 that extends longitudinally

of the housing 4 and along the central wiring gutter 22, and is supported in spaced relation with respect to the bottom 3 of the housing by means of conductive bridges 34 that serve to support the bus bar and to connect the corresponding terminals 27 of each panel thereto. The bridges 34 are of inverted U-shape and, consequently, support the bus bar at a point above the upper faces 10 of the panels, thereby providing ample space beneath the bus bar 33 in which conductors 35, that are connected to the auxiliary feed terminals 26, may extend. The conductors 35 are insulated and extend exteriorly of the housing through the two bushings 18 and are provided with terminals 36 that are connected to cross conductors 37 that extend transversely across the metering bars 20 in the auxiliary housing 5.

20 The bars 37 are mounted, at one end, on the terminals 36 and, at the other end, upon insulating pedestals 38 and are disposed above the bars 20, as indicated in Fig. 3. Each bar is provided with a sliding contact member 39 having a pair of flexible contact jaw members 41 that are adapted to yieldingly engage opposite sides of any selected metering bar 20. The sliding contact member 39 is disengaged from the bars 20 by a turning movement which withdraws the contact jaws out of engagement with the bars. It will be seen, therefore, that any conductor 35 may be selectively connected to any preferred metering bar. Any branch circuit may, therefore, be connected to any selected meter by connecting its respective contact member 39 with a metering bar that is connected to the selected meter.

40 The panels 21 are mounted upon Z-bars 42 and 43 which serve to support the panels in spaced relation with respect to the bottom of the housing, the latter serving to constitute, together with the adjacent ends of the panels, a deep wiring gutter having a portion of greater width at the bottom thereof in which the wires 35 may be disposed. It will be apparent that the wiring gutter is of such size as to accommodate a considerable number of wires and, consequently, any desired number of panels may be accommodated, only two, however, being shown for the purpose of illustration.

55 The circuit through the metering mechanism is as follows: current flows from the feed conductor 13 through the branch feed conductor 40 to the current coil 16 of the meter 17, thence through conductor 19, metering bar 20, sliding contact member 39, cross bar 37, terminal 36, conductor 35, auxiliary feed terminal 26, one of the switch arms of the switch 23, fuse 25, load conductor 31 through the load to conductor 32, load terminal 29, fuse terminal 25, the other switch arm of the switch 23, the auxiliary feed conductor 27, the bridge 34 to the neu-

tral bus bar 33 that is connected to the terminal 14.

Access to the live terminals and the exposed bus bar is prevented by means of a pan 44 that is mounted in the compartment 70 9 upon pedestals 45. The pan is provided with openings 46 through which the operating handles 47 of the switches project. The pan is closed by means of a cover 48 which is hinged to a main door 49 that, in turn, is hinged to the cover 8. The door 49 covers the inner panel compartment. The fuses 25 are accessible only when the door 49 is opened. Access may be had to the wiring gutters by removing the cover 8.

80 While I have described and illustrated but one embodiment of my invention, it will be apparent to those skilled in the art that various changes, modifications, substitutions, additions and omissions may be made 85 in the apparatus illustrated without departing from the spirit and scope of my invention, as set forth in the appended claims.

I claim as my invention:

1. Metering-panel mechanism comprising 90 a housing, a pair of panel devices having current-controlling members thereon connected to a load circuit and to auxiliary feed terminals and so disposed in the housing as to provide a central wiring gutter between 95 the panel devices, metering bars, a feed bus bar extending along the central wiring gutter, a conductive support for connecting an auxiliary feed terminal to the bus bar and for supporting the bus bar above the wiring 100 gutter, and insulated conductors connected to auxiliary feed terminals and extending along the central wiring gutter and having means whereby they may be connected to any selected metering bar.

105 2. Metering-panel mechanism comprising a pair of panel devices having current-controlling members thereon connected to a load circuit and to auxiliary feed terminals and so disposed as to provide a central wiring gutter between the panel devices, a feed bus bar extending along the central wiring gutter, a conductive support for connecting an auxiliary feed terminal to the bus bar and for supporting the bus bar between the panel 110 devices, metering bars and an insulated conductor connected to one of the auxiliary feed terminals and having means whereby it may be connected to any selected metering bar.

115 3. Metering-panel mechanism comprising 120 a housing, a pair of panel devices having current-controlling members thereon connected to a load circuit and to auxiliary feed terminals and so disposed in the housing as to provide a central wiring gutter between 125 the panel devices, metering bars, a feed bus bar extending along the central wiring gutter, a conductive support for connecting corresponding auxiliary feed terminals of the panel devices to the bus bar and for 130

supporting the bus bar between the panel devices, and insulated conductors connected to auxiliary feed terminals and extending along the central wiring gutter and having means whereby they may be connected to any selected metering bar.

4. Metering-panel mechanism comprising a housing, a pair of panel devices having current-controlling members thereon connected to a load circuit and to auxiliary feed terminals and so disposed in the housing as to provide a central wiring gutter between the panel devices, metering bars disposed exteriorly of the housing, a feed bus bar extending along the central wiring gutter, a conductive support for connecting an auxiliary feed terminal to the bus bar and for supporting the bus bar above the wiring gutter, and insulated conductors connected to auxiliary feed terminals and extending along the central wiring gutter and having means whereby they may be connected to any selected metering bar.

5. Metering-panel mechanism comprising a pair of panel devices having current-controlling members thereon connected to a load circuit and to auxiliary feed terminals and so disposed as to provide a central wiring gutter between them for receiving insulated conductors, a main feed bus bar extending along the wiring gutter and a conductive support for supporting the bus bar and electrically connecting it to corresponding auxiliary feed terminals of the panel devices.

6. Metering-panel mechanism comprising a housing, a pair of panel devices having current-controlling members thereon connected to a load circuit and to auxiliary feed terminals and so disposed in the housing as to provide a central wiring gutter between the panel devices, main feed terminals in the housing, a permanent bus bar connected to one of the main feed terminals and extending along the central wiring gutter, a conductive bridge for connecting corresponding auxiliary feed terminals to the bus bar, meters connected to one of the main feed terminals, metering bars disposed exterior of the housing and connected to separate meters and insulated conductors connected to one of the auxiliary feed terminals and extending along the central wiring gutter beneath the conductive support and having means whereby they may be connected to any selected metering bar.

7. Metering-panel mechanism comprising a housing having conductor outlets, a plurality of panel devices having current-controlling members thereon connected to load terminals and to auxiliary feed terminals and to auxiliary feed terminals 60 and so disposed in the housing as to provide a central wiring gutter between the panel devices and a central wiring gutter between the panel devices, main feed terminals in the housing, a permanent bus bar connected to one of the main feed terminals and extending along the central wiring gutter, a conductive bridge for connecting corresponding auxiliary feed terminals to the bus bar, meters connected to one of the main feed terminals, metering bars disposed exterior of the housing and connected to separate meters and insulated conductors connected to one of the auxiliary feed terminals and extending along the central wiring gutter beneath the conductive support and having means whereby they may be connected to any selected metering bar.

8. Metering-panel mechanism comprising a housing, a plurality of panel devices having current-controlling members thereon connected to a load circuit and to auxiliary feed terminals and so disposed as to provide a central wiring gutter between the panel devices, supports extending transversely of the panel devices and in spaced relation with respect to the bottom of the housing and for constituting together with the ends of the panel devices a central wiring gutter, a main feed bus bar extending along the wiring gutter, conductive bridge members for connecting corresponding auxiliary terminals to the bus bar and for supporting the bus bar above the panel members whereby ample clearance is provided for metering conductors in the wiring gutter.

9. In a metering panel, the combination with a support, a pair of spaced panel devices mounted thereon having circuit-controlling elements thereon provided with terminal members, and a permanent bus bar extending between the panel devices, of conducting means for supporting the bus bar in spaced relation with respect to the bottom of the housing and for connecting corresponding terminals of the opposite panel devices and insulated conductors connected to other of the said terminal members and extending beneath the said supporting means and between the said panel device.

In testimony whereof, I have hereunto subscribed my name this 25th day of February 1922.

OLIVER S. JENNINGS.
